UNITED STATES PATENT OFFICE.

GEORGE M. BRADLEY, OF LANSING, MICHIGAN.

AUTO BURGLAR-ALARM.

1,327,266.

Specification of Letters Patent. Patented Jan. 6, 1920.

Application filed November 24, 1917. Serial No. 203,710.

To all whom it may concern:

Be it known that I, GEORGE M. BRADLEY, a citizen of the United States, residing at Lansing, in the county of Ingham and State 5 of Michigan, have invented new and useful Improvements in Auto Burglar-Alarms, of which the following is a specification.

This invention relates to an auto burglar or thief alarm adapted particularly for use 0 upon automobiles, for sounding an alarm when an attempt is made by an unauthorized person to start the engine of the automobile and drive off the vehicle.

The primary object of the invention is to 5 provide an alarm whistle which may be connected with the engine in such a manner that when the engine is started into action an alarm will be sounded.

A further object of the invention is to 10 provide an alarm whistle which may be connected with one of the engine cylinders so that upon the movement of the piston therein a portion of the explosive charge or exhaust from the engine cylinder will be 15 forced out through the whistle, thereby sounding the alarm.

A further object of the invention is to 20 provide an alarm device of the character described which is adapted to be controlled by 10 a lock or similar device and set and locked in operative position for action when the owner leaves the vehicle standing, so as to be operated if the engine is started during 25 the absence of the owner.

The invention consists of the features of 30 construction, combination and arrangement of parts, hereinafter fully described and claimed, reference being had to the accompanying drawing, in which:—

Figure 1 is a view showing a portion of 35 an automobile and illustrating the application of the invention.

Fig. 2 is a vertical longitudinal section 40 through the whistle and adjacent end of the controlling shaft.

Fig. 3 is a vertical section taken on the 45 line 3—3 of Fig. 2.

Fig. 4 is a sectional view through the dash 50 board of the vehicle and the adjacent end of the controlling shaft and its casing.

In carrying my invention into practice, I 55 provide an alarm device 1 comprising, a bowl 2 from which rises a sound tube 3 provided with suitable perforations 4 for the escape of the air or sounding fluid. Disposed between the top of the bowl and the

base of the sound tube 3 is a perforated horizontal partition or diaphragm 5, and extending upwardly from said partition to the top of the sound tube 3 is an imperforate vertical partition 6 separating said sound tube into sounding chambers or compartments 7 and 8. The fluid under pressure entering the bowl passes upwardly through the perforated diaphragm 5 and enters the sound chambers 7 and 8 of the sound tube 3 and escapes through the sound outlets thereof, thus sounding the whistle. Disposed within the chamber 8 is a horizontal partition 9 operating as a baffle to control the flow of the sounding fluid to vary the sound produced by the whistle chamber 8 with respect to that produced by the whistle chamber 7, whereby a distinctive sound of a certain character is produced.

The bowl 2 is threaded or otherwise secured at its lower end in the outlet of a valve or cock 10 which is provided at its lower or inlet end with a stem 11 projecting downwardly through the base or bottom wall 12 of a guard casing or shell 13 inclosing the cock and parts of the whistle, said shell being provided with perforations 14 for the escape of the sound to the atmosphere and acting as a protecting medium to guard the whistle from injury and to prevent the same from being damaged or destroyed by malicious parties. The stem 11 is connected by a coupling 15 to the upper end of a conducting pipe 16, which conducting pipe 16 is threaded at its lower end into the threaded aperture of a cylinder of the engine or motor 17 within which the priming cock is usually fitted, thus establishing communication between the whistle and a cylinder of the engine for the flow of the fluid mixture or products of combustion to the whistle to sound the whistle, under certain conditions, when the engine or motor is in action. In practice, the alarm whistle is applied to the engine by simply removing one of the priming cocks and substituting the whistle in its place.

The valve member of the cock 10 is provided with an exteriorly projecting stem 18 to which is secured a gear segment 19. This segment 19 meshes with a gear 20 upon the adjacent end of a controlling or actuating shaft 21. The shaft 21 extends from the shell or casing 14 to the dash board 22 of the automobile, and said shaft is preferably in-

closed throughout its length within a protecting pipe or casing 23, whereby damage to the shaft or interference therewith in an attempt to prevent the operation of the 5 alarm will be prevented. The rear end of the shaft terminates in an angular projection 24 which fits within a rotary socket 25 forming part of the locking mechanism of a lock device 26 mounted upon the dash board 10 22, which lock device 26 may be of the Yale type. When this lock device is turned in one direction to a locked position it will rotate the shaft 21 in the proper direction to actuate the gear 19 so as to open the valve or 15 cock 10 to establish communication between the engine cylinder and whistle, to render the whistle operative, and the shaft and cock will be locked in such position as long as the locking mechanism of the lock 26 re- 20 mains in locking position. When, on the other hand, the locking mechanism of the lock 26 is turned in the opposite direction to unlocking position, the shaft 21 will be rotated in the opposite direction to close the 25 valve or cock 10 and thus cut off communication between the engine cylinder and whistle, thus rendering the whistle inoperative, which is its normal condition in the ordinary running or operation of the vehicle. 30 It will thus be understood that the lock is normally maintained in unlocked position and the valve in closed position until such a time as the owner of the automobile desires to set the whistle for operation. This may 35 be when he wishes to park or leave his machine standing for any length of time, in order that the alarm mechanism may be set to sound an alarm when any unauthorized person starts the engine and attempts to 40 make off with the vehicle. To set the alarm, the operator simply turns the lock to locked position by means of a proper key, which is then removed from the lock, whereby the valve or cock 10 will be moved to open position 45 and locked in such position. Communication between an engine cylinder and the

whistle will then be established, so that if the engine should be started into action the formation or firing of a charge in the cylinder communicating with the whistle will 50 cause the expulsion of the charge to the atmosphere through the whistle, thus sounding an alarm and warning the owner of the vehicle or others in the vicinity that an unauthorized person has started the engine of 55 the machine, whereupon measures may be taken to prevent the theft of the machine as will be readily understood. It will be seen from the foregoing description that the alarm device provided for the purpose de- 60 scribed is simple of construction and may be manufactured and installed at a comparatively low cost, and that when set for action it will give an alarm as soon as the engine is started, and that as the alarm is locked in 65 operative position the engine can not be started without an alarm being given and the alarm can not be thrown out of action except by one familiar with the actuation of the controlling shaft and possessed of the 70 proper type of key.

Having thus fully described my invention, I claim:

In an alarm device for automobiles, the combination of a dashboard, a motor, an 75 alarm device adapted to be operated by expulsion of fluid products from the motor, an actuating element fitted in the dashboard, a perforated guard casing inclosing the alarm device, a valve inclosed within the guard 80 casing and controlling communication between the alarm device and motor, gearing inclosed within the guard casing for opening and closing the valve, a rod or shaft extending between and connecting said gearing with said actuating element, and a guard tube extending between and connecting the 85 perforated guard casing with the dashboard and inclosing the rod or shaft between the actuating element and the gearing. 90

In testimony whereof I affix my signature.

GEORGE M. BRADLEY.
